UNITED STATES PATENT OFFICE.

WILLIAM BAILEY STURGES, OF LOTTIE, LOUISIANA.

AUTOMATIC RAILWAY GATE.

Application filed October 12, 1923. Serial No. 668,168.

To all whom it may concern:

Be it known that I, WILLIAM B. STURGES, a citizen of the United States, residing at Lottie, in the parish of Pointe Coupee and 5 State of Louisiana, have invented certain new and useful Improvements in Automatic Railway Gates; and I do hereby declare the following to be a full, clear, and exact description of the invention, such as will enable others skilled in the art to which it 10 appertains to make and use the same.

The present invention relates to improvements in automatic railway gates and has for an object to provide for the raising of 15 gates across the road-way at a railroad intersection by the action of the train in approaching the crossing.

Other objects of the invention are to provide an improved mechanical device disposed in the path of the locomotive to be depressed by a part thereof during the travel of the locomotive over a section of the track sufficiently far from the intersection to insure that the gates will be elevated in good 25 time before the arrival of the train; to provide improved gates normally lying below the track level and adapted to be raised by the improved device to a position barring the crossing; and to unite the gates with the 30 automatic raising mechanism by a simple and effective construction which will communicate movement to the gates without lost motion.

With the foregoing and other objects in 35 view, the invention will be more fully described hereinafter, and will be more particularly pointed out in the claims appended hereto.

In the drawings, wherein like symbols refer to like or corresponding parts throughout the several views,

Figure 1 is a top plan view of a railway crossing showing the gates and the apparatus for operating the same.

Figure 2 is a longitudinal section taken through the track at the crossing with the parts in a normal position, the gates being down.

Figure 3 is a similar view with the gates raised.

Figure 4 is a cross section taken on the line 4—4 in Figure 1.

Figure 5 is a transverse section taken on the line 5—5 in Figure 1, and

Figure 6 is a similar view showing the 55 raised position of the gates.

Referring more particularly to the drawings, 1 and 2 designate the rails and 3 the ties supporting the same while the road is designated generally at 4.

To either side of the road are elongated ties or beams 5 and 6 having base members 7 and 8 thereon and posts 9 standing erect or vertical base members held in place by diagonal braces 10. The gates 11 are made 65 of substantially U shape construction having the side arms 12 pivoted at their free ends as indicated at 13 to the outside faces of the blocks 5 and 6 and adapted when elevated to strike the post 9 at a suitable elevation to bar the crossing. Each free end 70 of the gate arms 12 is provided with a diagonal extension 14 lying in rear of the pivot point 13, to which extensions are coupled rods 15 lying parallel with the beams or 75 ties 6 and extending approximately to a central point between the rails being guided in the clips 16 attached to said ties. A lug 17 on the extension 14 provides for receiving one end of a coil spring 18 affixed as at 19 80 to the tie or some other stationary part, the spring acting to restore the gates to a normal low position indicated in Figures 1 and 5.

The inner ends of the rod 15 are connected 85 to chains 20 or other flexible connections which extend about the pulleys 21 carried in a block 22 secured as by bolts 23 to the central portion of the beam 6. The chains 20 are joined to a connecting plate 24 lying 90 at the head of a rod 25 which extends and is suitably guided for a distance along the track and approximately midway between the rails 1 and 2. Beams 26 and 27 are mounted upon the ties 3 at a desired distance 95 from the crossing and covering a suitable distance, these beams having pins 28 journaled therein with spacing sleeves 29 on the pins between the beams. Links are pivoted upon the pins between the spacing sleeves 100 and comprise straight members 30 and offset members 31 riveted or otherwise secured together as indicated at 32 and having secured between the upper spaced ends thereof as by pivot 33 a shoe 34 having an enlarged head and sloping ends as indicated in Figures 2 and 3. The intermediate link is provided with a bell crank extension 35 pro-

jecting downwardly between adjacent ties and being secured to a chain or other flexible connection 36 extending to a pulley 37 and being connected to the other end of the 5 rod 25.

In operation the springs 18 which are four in number, being connected to each pair of 10 arms of both of the gates 11, normally hold the gates lowered as shown in Figures 1 and 5, and in this position the trip shoe 34 is elevated above the track as represented in Figure 2. This condition of the parts prevails until a locomotive approaching the 15 crossing strikes the curved end of the trip shoe, causing the shoe to move along in the same direction and at the same time lowering the shoe as indicated in Figure 3 which causes a movement of the bell crank arm 35 away from the crossing, exerting a pull 20 upon the chain 36 and rod 25 which is imparted to the connecting plate 24 and its chains 20. The chains are thus pulled toward one another drawing upon the rods 15 and swinging the gates about the pivot 25 points 18 until they arrive at the upright position shown in Figure 6, where they are arrested by the standards or posts 9. Here they interpose an effective barrier to the crossing and act as a signal to announce 30 the approach of the train. In securing this movement the springs 18 are distended as illustrated in Figure 6 and are held in this potential position until the locomotive is free of the trip shoe 34, whereupon the 35 springs are contracted and draw all of the parts back to the initial position.

It will be understood that a second trip shoe may be placed to the opposite side of the crossing and coupled in a similar way 40 to the other sides of the gate arms to enable trains coming from an opposite direction to also close the gates but inasmuch as this is merely a duplication of parts, it has not been illustrated.

It will be further appreciated from the 45 foregoing that the present invention provides a compact and effective gate closing mechanism which is operated automatically by the approach of a train and which will therefore eliminate the dangers incident to 50 errors arising from human agency.

It is obvious that various changes and 55 modifications may be made in the details of construction and design of the above specifically described embodiment of this invention without departing from the spirit thereof, such changes and modifications being restricted only by the scope of the following claims.

60 What is claimed is:

1. An automatic railway gate comprising a 65 gate member situated at a road crossing and being pivoted at its lower portion remote from the railroad and below the surface of the roadway, said gate adapted in its open

position to lie adjacent the near rail of the railroad, means actuated by a train approaching the crossing for automatically raising the gate about its pivoted point into a substantially upright position, and other 70 means in opposition thereto for restoring the gate to the open position, substantially as described.

2. In an automatic railway gate, the combination of a substantially inverted U shape 75 member having its free ends pivoted below the surface of the roadway at the side of the railroad, said gate adapted to swing upwardly to bar the crossing, means arranged in the path of the locomotive and having connection to the gate for raising the same upon the approach of a train, and resilient means acting in opposition to said last named means for restoring the gate automatically to the low position upon passage of the train, substantially as described. 85

3. In an automatic railway gate, the combination of a gate being pivoted at its lower end to swing at right angles to the path of a railway and having extended arms, connections to said arms extending to a central point beneath the railroad and lying along such railroad, and trip means adapted to be shifted by a passing locomotive and having connection to said connections for raising 95 the gate, substantially as described.

4. In an automatic railway gate, the combination of a pair of gate members situated at opposite sides of the crossing and adapted to swing down to opposite directions toward the track and to lie substantially flush with the roadway, a trip shoe lying between the rails at a distance from the crossing and adapted to have a longitudinal movement of the railway and a downward movement, connections to said trip lever and to both of the gates for simultaneously raising said gates upon the longitudinal and downward shifting of the trip shoe, substantially as described. 105

5. In an automatic railway gate, a pair of gate members consisting of substantially U shape members placed in inverted positions and pivoted at their lower portions at opposite sides of the railroad, such members adapted to swing down toward one another and lie approximately flush with the roadway, means for encountering the gates in their upright position, said gates for extensions below their pivoted points, rods connected thereto and lying transversely of the railroad, a connecting plate moving longitudinally of the railroad having connection to both of said rods, a rod connected to such connecting plate, a trip shoe mounted for longitudinal and downward movement having connection to said last named rod, substantially as described. 115 120 125
